DEVICE FOR WINDING ARMATURES

Vladimir C. Mironowicz, Sioux City, Iowa, assignor to Wincharger Corporation, Sioux City, Iowa, a corporation of Minnesota

Application December 22, 1941, Serial No. 424,026

2 Claims. (Cl. 242—13)

My invention pertains to a device for winding armatures.

An object of my invention is to provide in a very simplified manner, an arrangement in combination with standard winding chucks to simplify the winding of armatures, and to also reduce the time for winding the same.

A further object of my invention is to provide such an arrangement wherein the necessary loops for attachment to the commutator are taken off in a separated condition and such loops provided without the necessity of forming by hand.

With these and other objects in view, my invention consists in the construction, arrangement, and combination of the various parts of my device, whereby the objects contemplated are attained, as hereinafter more fully set forth, pointed out in my claims, and illustrated in the accompanying drawings, in which:

Figure 1 is a side elevation illustrating the entire device,

Figure 2 is an enlarged detail in elevation showing a portion of the winding device, and

Figure 3 is a plan view of Figure 2.

My invention contemplates an improvement over existing armature holding jaws or chucks to facilitate the winding operation especially with reference to the formation of the loops in the turns which are taken off for attachment to the commutator.

I have used the character 10 to designate a platform supporting the bracket 11 to which bracket are attached the members 12 and 13, the member 12 including a standard friction portion at 14 and the member 13 being attached to the pulley 15. Resting on the base 10 is a can 16 which receives a spool of armature wire which wire is indicated by the character 17 and which travels over the pulley 15 and thence under the further pulley 18, over the further pulley 19 and thence to the armature which is indicated generally by the character 20. The pulley 19 is pivotally supported at 21 to the rod 22 which is pivoted at 23 to the bracket 11 and attached at 24 to the rod 22 is the spring 25 which is attached at 26 to the bracket 11. An electric motor 27 is adapted to drive the arrangement for winding the required number of turns within the armature slots 28 (see Figure 3) and attached to the motor shaft 29 is the supporting fixture including the ring 30 which extends integrally into arms 31 which merge with the member 32 which is parallel to the ring 30, the member 32 including a hub 33 which is threadably engaged with the shaft 29 and locked thereto.

Attached to the member 32 is a guide member 34 which slidably receives the carriages 35 and 36 which carriages are threadably engaged with the screws 37 terminating in knurled portions 38, the inner ends of the screws 37 being rotatably secured in the flange 39 attached to which flange 39 is the abutment member 40 which is spring urged by means of the spring 41 against the armature 20. Pivotedly attached to the carriage 35 at 42 is the lengthened flat bar 43 to which is attached the series of three or more vertical retaining pins 44 which pins are preferably of increasing height rearwardly. Also attached to the carriage 35 is the bracket 45 which terminates in gripping jaws 46 having the rounded surface at 47 and the upper inwardly inclined portions 48. Attached to the member 36 is a further bracket 49 which terminates in a similar jaw 46 which is the same as the jaw 47 with the exception however that it is in an inverted position with respect thereto. Attached to the carriage 36 is a screw 50 which is adapted to engage against the wire retaining clip 51.

Many of the features herein illustrated apply to more or less standard procedures in the art, the jaws 46 serving to grip and support the armature 20 in the desired position leaving an armature slot 28 adjacent to each jaw so that when the motor 27 is turned in the direction of the arrow 52 the wire coils will be wound between opposite slots as shown more clearly in Figure 3, the curvature of the jaws 46 having the tendency of causing the wire to pass into the slots 28 which slots also include the usual insulating fibres 53. The screws 37 are turned inwardly or outwardly to carry the jaws 46 against the armature and to provide adjustment as to size.

The customary practice in using such an arrangement has been for the operator to allow the motor 27 to turn the required number of revolutions indicated by the revolution counter 54 (see Figure 1) which counter is operated from the flexible shaft 55, and thence to take off the leads in the form of a loop and to hold such leads momentarily by hand, and thence to successively wind further windings in the same slot and form other loops by hand which loops are to be attached to the commutator bars.

However, I provide in the jaws 46 an upper slot 56 and a lower slot 57 which are machined or otherwise formed, of a substantial depth beneath the outer surface of the jaws 46. By the use of this arrangement, after each required number of turns are made by starting the motor

27 and then stopping the same, the ending of each series of turns is brought up through the upper slot 56 and thence over the lowest pin 44 as shown in Figure 3 and thence through the lower slot 57 and back upwardly through the opposed slot 28, and the ending of the next series of turns in the same slot 28, is then brought over the next or second pin etc.

The clip 51 is used to hold the end of the wire 17 before the winding operation is performed. Since the curvature of the portions 48 is adapted to guide the wire downwardly through the adjacent slots 28 of the armature 20, these curved portions have a tendency of smoothly guiding the wire into the slots 56 as well as 57 to provide a quicker operation. After the opposed pairs of slots 28 are wound as shown in Figure 3, the jaws 46 are loosened and the armature is then turned until a further opposing pair of slots 28 are ready for the winding operation when the same process is again repeated.

The use of such slots besides providing the required separation in the loop as well as being positioned in the proper location for guidance into the same, provide in combination with the pins 44 a method of retaining the loops in a fixed separated position from the armature which eliminates the objectionable feature of the loops being pulled back into the winding again when they are formed by hand. A spring 58 is attached at 59 and 60 to retain the member 43. The same arrangement of slots on the opposite jaw permits use thereof when the rotating portions of the device happen to fall in that particular position, so that the loops can be formed at practically any position of the arrangement.

I have found through the use of this device that the time for winding armatures is materially reduced in that the aforesaid slots receive the loop wires quickly through the guiding

action of the jaws and in so doing also simplify the process.

Some changes may be made in the construction and arrangement of the parts of my invention without departing from the real spirit and purpose of my invention, and it is my intention to cover by my claims any modified forms of structure or use of mechanical equivalents which may be reasonably included within their scope.

10 I claim as my invention:

1. In combination with a guide, clamping jaws for holding armatures in an armature winding machine, each of said jaws having curved portions extending toward its clamping edge and having entry slots formed in the surfaces of said jaws for receiving armature end loops therein, including an upper slot angularly positioned with respect to the jaws and merging with the curved portion of the jaws to provide smooth entry of wire therein for receiving one side of said loop, and a lower angularly positioned slot for receiving the other side of the loop.

25 2. In combination with a guide, clamping jaws for holding armatures in an armature winding machine, each of said jaws having curved portions extending toward its clamping edge and having entry slots formed in the surfaces of said jaws for receiving armature end loops therein, including an upper slot angularly positioned with respect to the jaws and merging with the curved portion of the jaws to provide smooth entry of wire therein for receiving one side of said loop, and a lower angularly positioned slot for receiving the other side of the loop, means for holding said loops in separated position including a plurality of spaced pins, and a frame supporting said pins.

30 35 40 VLADIMIR C. MIRONOWICZ.
